[57] CLAIM

The ornamental design for the SCSI connector, as shown and described.

DESCRIPTION

FIG. 1 is a top, right and front perspective view of an SCSI connector showing our new design. The broken line matter is included for the purpose of illustrating the article, *per se*, in which the design is embodied and forms no part of the claimed design;

FIG. 2 is a left side plan view;

FIG. 3 is a back plan view; and,

FIG. 4 is a bottom plan view.
